(57) **CLAIM**

The ornamental design for a display shelf, as shown and described herein.

DESCRIPTION

FIG. 1 is a perspective view of a first embodiment of a display shelf;

FIG. 2 is a front elevation view thereof;

FIG. 3 is a rear elevation view thereof;

FIG. 4 is a side elevation view thereof;

FIG. 5 is another side elevation view thereof;

FIG. 6 is a top elevation view thereof;

FIG. 7 is a bottom elevation view thereof;

FIG. 8 is a perspective view of a second embodiment of a display shelf;

FIG. 9 is a side elevation view thereof;

FIG. 10 is another side elevation view thereof;

FIG. 11 is a front elevation view thereof;

FIG. 12 is a rear elevation view thereof;

FIG. 13 is a top elevation view thereof;

FIG. 14 is a bottom elevation view thereof;

FIG. 15 is a perspective view of a third embodiment of a display shelf;

FIG. 16 is a side elevation view thereof;

FIG. 17 is another side elevation view thereof;

FIG. 18 is a front elevation view thereof;

FIG. 19 is a rear elevation view thereof;

FIG. 20 is a top elevation view thereof;

FIG. 21 is a bottom elevation view thereof;

FIG. 22 is a perspective view of a fourth embodiment of a display shelf;

FIG. 23 is a side elevation view thereof;

FIG. 24 is another side elevation view thereof;

FIG. 25 is a front elevation view thereof;

FIG. 26 is a rear elevation view thereof;

FIG. 27 is a top elevation view thereof; and,

FIG. 28 is a bottom elevation view thereof.

The broken lines shown in the drawings are to illustrate environmental features only and form no part of the claimed design.
